ANTENNA SYSTEM

William H. Warren, New York, N. Y., assignor to
 Western Electric Company, Incorporated, New
 York, N. Y., a corporation of New York

Application February 21, 1935, Serial No. 7,501
 In France April 25, 1934

15 Claims. (Cl. 250—11)

The present invention relates to improvements in antenna systems, and more particularly in systems comprising a plurality of directional antennas or antenna arrays.

Heretofore, in long distance broadcasting of news and in certain transcontinental transmissions, it has been necessary to provide several directional systems directed in different directions, these systems being supplied simultaneously with energy modulated in the same manner at least for high frequency. Also each directional system has been ordinarily associated with a separate radio transmitter.

One object of this invention is to transmit or receive energy in several predetermined directions utilizing a single aerial system.

Another object of the present invention is to transmit, efficiently, energy in several directions with a minimum amount of apparatus.

Still another object of this invention is to radiate a maximum amount of the energy supplied by a transmitter to a radiating system.

According to this invention a plurality of directional arrays, preferably aperiodic, is provided, each of the arrays serving to establish directive communications in different directions and said arrays being fed by a common high frequency feeding system on which one or several frequency bands may be transmitted. The several directional arrays are associated either in series or in parallel or in combined grouping, with the transmission system, the arrangement being preferably such that a predetermined quantity of energy is radiated by each antenna network.

The invention will be better understood by referring to the attached drawings on which like reference characters denote elements of similar function, and on which:

Fig. 1 represents a directional antenna of the well-known "diamond" or "rhombic" type which is disclosed in the application of E. Bruce, Serial No. 513,063, filed February 3, 1931;

Fig. 2 shows a series or tandem arrangement of two such rhombic antennas;

Fig. 3 shows a parallel arrangement of two rhombic antennas;

Fig. 4 shows a coupling arrangement which is suitable for transmitting two large bands of frequencies and for associating a rhombic antenna with a radio transmitter;

Fig. 5 shows the combination of a rhombic antenna and another antenna arranged to obtain a polarized radiation;

Fig. 6 shows an arrangement comprising a rhombic antenna and an inverted V of the type

disclosed in Patent 1,899,410, E. Bruce, February 28, 1933;

Fig. 7 represents a tandem arrangement of V antennas.

It is well-known that one of the properties of the rhombic antenna is its faculty of functioning efficiently for a considerable band of frequencies. This property, however, cannot be entirely utilized when the antenna is rendered unidirectional by means of a reflector because a reflector which would be suitably placed for a given frequency would not be suitably positioned for another frequency. In order to preserve the multi-frequency characteristic of the rhombic antenna and at the same time effect unilateral operation, the antenna is designed to have the same characteristic impedance as the feeding system and an absorbing line is connected to the distant end of the antenna, the characteristic impedance of the absorbing line being approximately equal to that of the antenna, whereby reflection of non-radiated energy is eliminated. In such an arrangement about half the total energy supplied to the feeding system and antenna is lost in the absorbing transmission line.

In accordance with this invention the energy feeding the absorbing line and otherwise lost is utilized to energize a second preferably directive antenna, this antenna being directed either in the same direction as the first antenna or in a different direction. Alternately, this energy otherwise lost may before or after passage through a suitable rectifier system be employed for metering the power radiated.

Referring to the drawings the system of the prior art illustrated by Fig. 1 comprises a radiating transmitter RT feeding a rhombic antenna A by means of a transmission line TL of any suitable type, such as a coaxial line or a line comprising parallel wires. An absorbing transmission line TL_a is connected to the distant end of the antenna A. Assuming that the loss in the transmission line TL is negligible, 50% of the energy supplied by the radio transmitter RT is radiated by the antenna A while the remaining 50% is dissipated in the absorbing transmission line TL_a, the loss in the terminating line TL_a being approximately 3 decibels. Instead of dissipating 50% of the energy in the absorbing transmission line, this energy or a part thereof is, in accordance with this invention, employed to feed a second antenna, as illustrated by Fig. 2.

In Fig. 2, RT designates a radio transmitter, TL a transmission line of any suitable type and A a rhombic antenna whose far end is connected by

transmission line TL' to a second antenna A' , at the distant end of which is placed an absorbing transmission line TLa . A coupling device CD such as illustrated by Fig. 4 is included in the line 5 TL . Arrows 1 and 2 indicate respectively the desired direction of operation for antennas A and A' . In an actual case, the absorbing transmission line TLa was formed of two galvanized iron wires 480 meters long and having diameters 10 of 2 to 3 millimeters. They were spaced at 20 centimeters between centers. To secure the same attenuation with shorter lines the wires may be formed of certain suitable alloys.

In the system of Fig. 2, if the losses in the 15 transmission lines TL are ignored, 50% of the power supplied by the radio transmitter RT is radiated by the transmitter A , 25% of the power is radiated by the transmitter A' , assuming that the losses in the transmission line TL' are negligible 20 and 25% of the energy is dissipated in the absorbing transmission line TLa . It will thus clearly be seen that a portion of the energy otherwise dissipated may be advantageously employed to drive another antenna, this antenna 25 being preferably provided with means for preventing reflection losses.

Fig. 3 illustrates two rhombic antennas A and A' connected in parallel. A radio transmitter RT feeds a transmission line TL of any suitable 30 type, this line being terminated by branch lines TL' and TL'' which feed the antennas A and A' in parallel. Antennas A and A' terminate, respectively, in absorbing transmission lines TLa and TLa' .

The distribution of energy in the system of 35 Fig. 3 is as follows: 25% of the energy supplied by radio transmitter RT is radiated by each of antennas A and A' , and 25% is absorbed by each of the lines TLa and TLa' . Comparing the tandem arrangement of Fig. 2 to the parallel arrangement of Fig. 3 it will be seen that in the case of a tandem connection only a small loss is sustained since there is only one dissipating line. Other advantages of the tandem array over the 40 parallel array are that a simple transmission system is employed and the impedance in which the radio transmitter RT discharges is approximately the same whatever the number of antennas fed. It should be noted that in the case 45 of the parallel system, special precautions must be taken to properly terminate line TL for efficient operation over a band of frequencies. To insure this the two auxiliary transmission lines TL' and TL'' may be extended to the radio 50 transmitter RT and connected in parallel at the output terminals of the power amplifying unit.

The tandem array of Fig. 2 permits the aperiodic characteristic, as well as the unidirectional 60 property, of each antenna to be retained so that one antenna may be directed in a certain direction while another is directed in a different direction. Also a definite quantity of energy may be 65 successively brought to the various antennas connected in tandem, a small part of this energy supplied finally arriving at the absorbing circuit whose function is to render the system electrically long and to prevent reflection losses. By 70 aligning groups of these antennas at various points increased directional propagation may be realized in different directions.

Expressed on a transmission basis, the first antenna is equivalent in efficiency to a single isolated rhombic antenna of the same dimension 75 and, in the case of a rhombic antenna having

sides four wave-lengths long, a gain of 15 decibels over an ordinary dipole is realized. The gain of the second antenna will be, in view of the energy received by the system, 3 decibels less than that achieved by the first antenna, the gain being about 12 decibels over the dipole. Each successive antenna will approximately lose 3 decibels in efficiency with respect to the preceding antenna. In the case of four antennas connected in tandem, the last antenna will still give about 6 decibels more than a dipole. Attenuators and other devices used in high frequency transmission circuits may be employed in the system for adjusting the amount of energy radiated by each antenna as desired. Thus, in the 15 case of directional antennas directed in diverse directions the quantity of energy radiated by each antenna may be regulated in accordance with the distance to be covered by the various transmissions.

Fig. 4 shows a coupling device permitting a rhombic antenna to be associated with a coaxial or concentric transmission line TL . The antenna is connected to the line conductors L_1 and L_2 which may be shunted by a preferably adjustable tuning condenser C_a . The line conductors L_1 and L_2 are connected through coupling condensers C to two impedance reducing transformers T_1 and T_2 connected in parallel. These transformers are constructed so as to have a unity coefficient 25 of coupling between the primary and secondary windings. For this purpose the secondary windings may each be formed by a certain number of spirals arranged in parallel, these spirals taking up about the same space as the primary winding. 30 The primary windings P_1 and P_2 are connected to the transmission line TL through coupling condensers C_1 and C_2 . In Fig. 4 a terminal of each primary winding is connected to ground since one of the conductors of the transmission line TL 35 is connected to ground.

The transformers T_1 and T_2 transmit different frequency bands. In a particular installation transformer T_1 was designed to transmit frequencies included between 4,500 kilocycles per 45 second and 12,000 kilocycles per second, and transformer T_2 to transmit the frequency band extending from 12,000 kilocycles per second to approximately 21,000 kilocycles per second. The attenuation was substantially constant for frequencies between 9,000 and 14,000 kilocycles per second. It may be added that in constructing the antenna care must be taken to avoid any irregularity, which would destroy the uniform character of the characteristic impedance. For 50 example, the insulators should be small and the wires should be of uniform dimensions and unassociated with conducting members such as the metal fixtures.

The invention may be employed in various 60 arrays and systems as, for example, the systems illustrated by Figs. 5, 6 and 7. Referring particularly to Fig. 5, the transmission line TL'' feeds through transformer T a transmission line TL which terminates in a transmitting antenna A' 65 of any type. This arrangement insures the use of energy which would otherwise be lost and which can be radiated by a directional or non-directional antenna. The phases of the currents of A and A' may be adjusted to obtain elliptically 70 polarized waves.

In Fig. 6 the antenna A' is a directive V antenna array comprising a plurality of V antenna elements V_1 , V_2 , V_3 , V_4 , connected to the auxiliary transmission line TL'' . The V antennas V_1 , V_2 , 75

V₃, V₄ are terminated, respectively, at their far ends by suitable resistances R₁, R₂, R₃ and R₄, which render the V antennas unilateral. These resistances may be directly connected to earth or, if the earth is not well defined, to the middle point of horizontal half wave-length counterpoises. Obviously, the absorption resistances terminating the V antennas may be replaced by radiating elements. The direction of maximum propagation in a horizontal plane of the rhombic antenna and of the V antenna array coincide, as indicated by arrows 3 and 4.

Fig. 7 illustrates a tandem arrangement of two V antenna arrays. In the system of this figure the radio transmitter RT feeds a transmission line TL to which are connected at points spaced a half wave-length V antennas V₁, V₂, V₃ and V₄ constituting an array. The far ends of these V antennas are connected to another transmission line TL' at points spaced a half wave-length. Transmission line TL', which may be of any length, supplies an array similar to that which has just been described and comprising V antennas V_{1'}, V_{2'}, V_{3'} and V_{4'}. The far ends of these V antennas are terminated in absorbing resistances connected to ground or to counterpoises such as those illustrated by Fig. 6. Between the two groups of antennas A and A', Fig. 7, impedance networks may be provided, such as filters, for causing the antenna A' to radiate different frequencies from those of the antenna A. The major directive lobes of the antennas A and A' may be similarly or differently directed.

It may be desirable to radiate different quantities of energy in specified directions, utilizing arrays connected in tandem or parallel. In the tandem arrangement the desired division between the power radiated in the several directions may be easily controlled within certain limits by properly orienting the different arrays since, as already pointed out, the successive arrays radiate gradually diminishing amounts of energy. In the parallel arrangement, the energy is divided according to the law of shunted circuits and equal amounts of energy may be radiated in the specified directions. It is clear that, in accordance with this invention, a single radiating system may be used for multi-channel and multi-directional operation, whereby for example, communication may be realized between a single transmitter and a certain number of receiving stations, any one of which may be adapted to receive one or more of the frequencies transmitted by the central radio transmitting station.

Although the invention has been described in connection with certain specific embodiments, it is to be understood that it is not to be limited to such embodiments. Obviously, different tandem or parallel arrangements, or combinations of such arrangements, arranged either for transmitting or receiving, may be satisfactorily employed without exceeding the scope of the invention.

What is claimed is:

1. In a radio system, a transmitter, a plurality of directive antennas, said transmitter being connected directly to one antenna and only through said antenna to the remaining antenna or antennas, and said antennas being oriented for effective operation in different directions.
2. In a radio system, a transmitter, a plurality of unilateral antennas connected in tandem and to said transmitter, said antennas being oriented for propagating energy in different horizontal directions.
3. In a radio system, a transmitter, a plurality

of rhombic antennas connected in tandem, the first of which is connected to said transmitter and the last of which is terminated in its characteristic impedance.

4. In a radio system, a transmitter, a plurality of rhombic antennas arranged in tandem, the first antenna being connected to said transmitter and the last being terminated in its characteristic impedance, said last antenna and the intermediate antennas each having an impedance equal to 10 the characteristic impedance of the preceding antenna.

5. In a radio system, a transmitter, a plurality of similar rhombic antennas connected in tandem, the first of which is connected to said transmitter and the last of which is terminated in its characteristic impedance, at least two of the antennas being oriented for propagation in different horizontal directions.

6. In a radio system, a transmitter, a rhombic antenna connected thereto, each side element of said antenna being a half wave-length longer than the projection of said element on the path of maximum wave propagation, substantially, a second antenna having an impedance equal to 25 the characteristic impedance of said first antenna, said second antenna being connected to said first antenna.

7. A radio system, a transmitter, a rhombic antenna connected thereto, each side element of 30 said antenna being a half wave-length longer than the projection of said element on the path of maximum wave propagation, substantially, a second antenna connected thereto and oriented to radiate waves polarized differently from the 35 waves radiated by said rhombic antenna.

8. In a radio system, a rhombic antenna connected to a V antenna, said V antenna constituting a means for rendering the rhombic antenna unilateral.

9. In a radio system, a transmitter, an antenna array connected thereto and comprising a unidirectional antenna oriented for maximum radiation in a given direction, a second array connected to said first array and comprising unidirectional antennas oriented for maximum radiation in a single given direction, the frequencies of operation for said arrays being different.

10. In a radio system, a transmitter, a plurality of antenna arrays each comprising V antennas, 50 each element of said V antennas being approximately a half wave-length longer than the projection of said element on the path of maximum propagation, said first antenna array being connected to said transmitter and second array being connected to said first array.

11. In a radio system, a transmitter, a plurality of antenna arrays each comprising V antennas, each element of said V antennas being approximately a half wave-length longer than the 60 projection of said element on the path of maximum propagation, said arrays being connected in tandem and each positioned for operation in a desired direction, and said transmitter being connected to the V antennas constituting one of the 65 end arrays.

12. In a radio system, a first antenna system, a second antenna system, a translation device connected through the first system to the second system, said second system constituting means 70 for rendering the first system uni-directional.

13. In a radio system, a first antenna comprising a pair of V-shaped elements having their directions of maximum radiant action superimposed, a second antenna, a translation device 75

connected through the first antenna to the second antenna, said second antenna having an input impedance equal to the characteristic impedance of the first antenna.

- 5 14. In a radio system, a first antenna arranged for operation over one frequency band, a second antenna system arranged for operation over another frequency band, a translation device connected through the first system to the second system, said second system having an input impedance suitable for rendering the first system unidirectional, an impedance connected to the second system for rendering said system unidirectional, and coupling means included between 10 said device and said antennas, said coupling

means comprising a transformer for passing one and a transformer for passing the other of said bands with the same attenuation.

15. In a radio system, a plurality of directive antenna systems each oriented for operation in a desired direction and each comprising a pair of V-shaped antenna elements, each element comprising two conductors, a translation device, said device being connected between and in series with the V-shaped elements of each antenna system, the conductors of each system having their directions of maximum radiant action superimposed and aligned with the desired direction of action for the system.

WILLIAM H. WARREN. 15
